A. G. SNIDER

DISPLAY DEVICE

Filed July 14, 1924

INVENTOR
Adolph A. Snider
BY
C. P. Goebel
his ATTORNEY

UNITED STATES PATENT OFFICE.

ADOLPH G. SNIDER, OF BROOKLYN, NEW YORK.

DISPLAY DEVICE.

Application filed July 14, 1924. Serial No. 725,779.

To all whom it may concern:

Be it known that I, ADOLPH G. SNIDER, a citizen of the United States, and a resident of Brooklyn, county of Kings, and State of New York, have invented certain new and useful Improvements in Display Devices, of which the following is a specification.

This invention relates to display devices and has for its primary object to provide a simply constructed collapsible device for use in show windows or upon counters whereby an attractive and novel display of merchandise may be made.

More particularly, in one embodiment of my present improvements I provide a main display panel having integral lateral extensions at one of its ends each consisting of a series of relatively foldable sections and adapted when set up to support an article to be displayed, said sections folding closely upon each other when the device is collapsed so that a large number of the display devices can be stored or packed in a comparatively small space.

It is a further general object of the invention to provide a device of this character which can be inexpensively produced from a sheet of material, preferably card board, by a single stamping or cutting operation of a suitably formed die.

With the above and other objects in view, the invention consists in the improved display device, and in the form, construction and arrangement of its several parts as will be hereinafter more fully described, illustrated in the accompanying drawing and subsequently incorporated in the subjoined claims.

In the drawing wherein I have shown one simple and satisfactory embodiment of the invention and in which similar reference characters designate corresponding parts throughout the several views:

Figure 1 is a perspective view showing my improved display device;

Figure 2 is a side elevation thereof;

Figure 3 is a front elevation, the parts being folded or collapsed; and

Figure 4 is a bottom edge or plan view of the device collapsed as shown at Figure 3.

For purposes of illustration, I have shown the main display panel 5 of the device cut or formed to represent an arrowhead, but it will, of course, be understood that this main panel may be made in various other shapes, forms and sizes in accordance with

the particular article of merchandise to be displayed or advertised. The front surface of said panel 5 is adapted to receive appropriate printed advertising matter.

To the rear face of the panel 5 and centrally thereof the narrow flap 7 on one edge of a supporting easel 6 is secured by means of a suitable adhesive. This easel 6 may be readily bent with respect to the flap 7 thereof to lie flat against the rear side of the panel 5, as seen in Figure 3, or extended to a position at right angles to the panel 5 as shown in Figure 2 when the device is arranged in display position.

The panel 5 as well as its supporting easel 6 is stamped or cut from suitable sheet material, preferably cardboard, and said panel 5 is provided at one of its ends with integral lateral extensions. Each of these extensions at its juncture with the panel is scored as at 8 to provide a hinge or fold line, and each extension is also provided with additional spaced scores 9, thereby forming a series of relatively foldable sections 10 in each extension. As herein shown, I have provided the device with three such foldable sections, but it will be manifest that a greater number of such sections might be provided in accordance with the desired form or shape to be produced when these extensions are set up in display position.

In the embodiment illustrated, when in display position, the relatively foldable sections of each of the lateral extensions on the main panel produce a supporting structure of general triangular shape in plan having the form of a truncated pyramid. The rear section 10 of each extension has its end edge disposed upon the rear side of the main panel 5 and adhesively secured thereto, as indicated at 11. This rear section also has a central vertical score line 12 therein so that it may fold upon itself. In spaced relation to its upper edge the rear section 10 is provided with a horizontal score line 13 whereby the relatively movable flap 14 is produced, it being understood that the ends of this flap are not connected with the other sections 10.

The forwardly extending converging panels or sections 10 have their upper edges obliquely cut as at 15, said upper edges being inclined downwardly and forwardly to the upwardly projecting spur 16 formed upon said panels at their hingedly connected ends. Each of said panels is also provided

at the upper rear ends of said inclined edges 15 with the upwardly extending lugs or extensions 17.

In the use of the display device above described, assuming that the lateral extensions are folded or collapsed as seen in Figure 3 of the drawings, the several sections 10 thereof are relatively moved or expanded to the position shown in Figure 1 in which the two relatively foldable parts of the rear sections 10 extend in a common plane. Of course, the two parts of the flanges or flaps 14 at the upper ends of these sections also are thus disposed in the same plane. These flanges are then folded downwardly and forwardly so that they extend between the two forwardly extending panels or sections 10 as clearly shown in Fig. 2 of the drawings. In this manner, the collapsible structure is thus firmly braced and sustained against accidental folding or collapse under the weight of the article. As also shown in Figure 2 of the drawings, the article to be displayed may then be positioned upon the inclined upper edges of the side panels or sections 10, the greater portion of the weight of the article being sustained by the upward spur projection 16 at the connected ends of these sections. It will be noted that the article does not contact with or rest upon the bracing flap or flange 14 or upon the upper end of the rear section 10. The two spaced supporting structures at the lower end of the main panel thus afford a firm and substantial base for the device and when the articles to be displayed are positioned upon these supports, the weight thereof operates to prevent the device being accidentally moved or blown over by air drafts. The displayed articles either exposed or contained in cartons, when arranged upon the spaced supporting structures, are directly associated with the advertising matter printed upon the main panel 5, thus providing a very attractive display which will arrest and hold the attention of the prospective purchaser.

When it is desired to collapse the device, it is only necessary to lift the flanges or flaps 14 of the rear sections 10, and then fold said rear sections inwardly between the two side sections along the score line 12, whereby the other sections 10 may be brought into close relationship, as shown in Figures 3 and 4 of the drawings. In this collapsed or folded condition of the device, a large number of display devices can be stored in a relatively small space or conveniently packed for shipment.

It will, of course, be understood that in addition to the printed advertising matter contained on the face of the main panel 5, the surfaces of the two front sections 10 of the lateral extensions may also contain additional printed advertising.

From the foregoing description considered in connection with the accompanying drawing, the construction and several advantages of my improved display device will be readily understood. It will be seen that such a device may be expeditiously and inexpensively produced in a single die stamping operation from cardboard or other sheet material and can, therefore, be furnished to retailers by manufacturers of the merchandise to be displayed without cost and without necessitating any appreciable increase in the retail selling price of the merchandise. While I have found the illustrated example of the invention very satisfactory, it will nevertheless be apparent that the device might be exemplified in various other alternative embodiments and I accordingly reserve the privilege of resorting to all such legitimate modifications in the form, proportion and relative arrangement of the several detail parts as may be fairly incorporated within the spirit and scope of the invention as claimed.

I claim:

1. A display device formed from a single sheet of material and comprising a main display panel and lateral extension integral with each side of said panel and each consisting of a plurality of relatively foldable sections movable with respect to each other and with relation to said panel from a folded position in the plane of the main panel into spaced open relation to each other with a number of the sections on each side projecting in front of the main panel to provide a many sided supporting structure, said sections adapted to receive and support an article to be displayed upon the upper edges thereof. 100

2. A display device formed from a single sheet of material and comprising a main display panel and lateral extensions integral with each side of said panel and each consisting of a plurality of relatively foldable sections movable with respect to each other and with relation to said panel from a folded position in the plane of the main panel into spaced open relation to each other with a number of the sections on each side projecting in front of the main panel to provide a many sided supporting structure, the upper edges of two of said sections on each side of the main panel being cut to extend obliquely downwardly and forwardly with respect to the main panel when the device is set up, and means for retaining an article to be displayed in position upon the oblique edges of said sections. 115

3. A display device formed from a single sheet of material and comprising a main display panel and lateral extensions integral with each side of said panel and each consisting of a plurality of relatively foldable sections movable with respect to each other 120

125

130

- and with relation to said panel from a folded position in the plane of the main panel into spaced open relation to each other with a number of the sections on each side projecting in front of the main panel to provide a many sided supporting structure, the upper edges of two of said sections on each side of the main panel being cut to extend obliquely downwardly and forwardly with respect to the main panel when the device is set up and each of said latter sections having vertical extensions at its forward upper edge to retain an article in display position thereon.

4. A collapsible display device constructed from a single piece of sheet material and comprising a main panel having integral extensions at one end projecting laterally from opposite side edges thereof, each of said extensions being scored to provide a plurality of relatively foldable sections movable with respect to each other and with relation to said main panel from folded position in the plane of the main panel to provide a many sided article supporting structure with a number of the sections on each side projecting in front of the main panel, and a bendable flap on one of said foldable sections adapted to be positioned between the other sections to provide a brace and prevent the collapse of the supporting structure.

5. A collapsible display device constructed from a single sheet of material and comprising a main display panel having extensions projecting laterally from opposite edges thereof, each of said extensions being scored at spaced points to provide a plurality of relatively foldable sections movable with relation to each other with respect to the main panel from folded position in the plane of the main panel to provide a many sided article supporting structure with a number of the sections on each side projecting in front of the main panel, when the device is set up, one of said sections being scored to fold upon itself when the structure is collapsed and said section having a bendable flap adapted to be positioned between the other foldable sections to brace the same apart and retain the structure in its set up position.

6. A collapsible display device constructed from a single sheet of material and comprising a main display panel having extensions projecting laterally from opposite edges thereof, each of said extensions being scored at spaced points to provide a plurality of relatively foldable sections movable with relation to each other and with respect to the main panel from folded position in the plane of the main panel to provide a many sided article supporting structure with a number of the sections on each side projecting in front of the main panel, when the device is set up, one of said sections being scored to fold upon itself when the structure is collapsed and said section having a bendable flap adapted to be positioned between the other foldable sections to brace the same apart and retain the structure in its set up position, said latter sections being provided with vertical extensions on the forward portions of their upper edges to retain an article to be displayed in position thereon.

In testimony that I claim the foregoing as my invention, I have signed my name hereto.

In testimony that I claim the foregoing as my invention, I have signed my name hereto.

ADOLPH G. SNIDER.
